TOY COMBINE

Kenneth E. Wisslead, Warsaw, Ill.

Application March 5, 1948, Serial No. 13,141

2 Claims. (Cl. 46—40)

1

This invention relates to toys and is more particularly directed to a miniature combine.

An object of the invention is the provision of a toy in simulation of a combine in which a beater and a screw conveyor are revolved by operative connections with the traction wheels of the toy, a header pivoted at one end on the main body of the toy with the other end being free for elevating the same, a manually operated bell crank raising or lowering the free end.

A further object of the invention is the provision of a toy in the form of a combine for harvesting grains in which a hopper is filled with sand or grains to be delivered to a bin by a screw conveyor actuated through connections with the traction wheels of the combine, a revolving mechanism disposed over a header simulating a beater being operatively connected with the actuating means for the conveyor, said header pivoted at the inner end thereof and provided with manual means for raising or lowering the other end, and likewise the beater which is supported in bearings carried by the header, a manually operated screw conveyor being employed for removing the sand or grain from the bin.

The invention will be best understood from a consideration of the following detailed description in view of the accompanying drawings forming part of the specification. Nevertheless, it is to be understood that the invention is not confined to the disclosure, being susceptible of such modifications which shall define no material departure from the salient features of the invention as expressed in the appended claims.

In the drawings:

Figure 1 is a side view in elevation of my toy which simulates a combine,

Figure 2 is a plan view of the toy with parts broken away,

Figure 3 is a fragmentary transverse vertical section taken along the line 3—3 of Figure 2, and

Figure 4 is a fragmentary transverse vertical section taken along the line 4—4 of Figure 1.

Referring more particularly to the drawings 10 designates a longitudinal beam connected to one end of a housing 11 of an axle 12 which extends transversely of the body 13 of the toy at the rear end thereof. An L-shaped beam 14 has an arm 15 secured at one end to an intermediate portion of the beam 10. The other arm 16 has its free end connected to the other end of the axle housing. The beams 10 and 14 may be channel shaped in cross section and are formed of thin sheets of crimped or corrugated steel. Traction wheels 17 and 17a are attached to the opposite ends of the axles.

2

The body 13 is constructed to resemble that same element in a combine used for harvesting grain. The body is in the form of a housing which is progressively tapered from the top to the bottom to provide spaced parallel V-shaped side walls, 20 and 21, a flat top 22, curved at its ends, and a front bottom panel 23. The lower ends of the side walls and the panel 23 are secured firmly to axle housing 11. The top 22 is provided with an elongated cover plate 25 hinged at 26 on the side walls of the body 13. A tapered hopper 27 has a transversely curved lower end 28 for the reception of a screw conveyor 29 carried by a shaft 30 extending beyond the side wall 21. A pulley 31 is secured to the extended end of the shaft. The conveyor 29 projects through the side wall 20 into a discharge bin 32 for delivering grain or sand which has been supplied to the hopper 27 (Fig. 2). The bin 32 has a tapered bottom with a channel 35, semi-circular in cross section, in which is mounted a manually operated screw conveyor 36. The channel is inclined (Fig. 3) and has its lower portion in a position to receive the grain or sand delivered by the screw conveyor 29. The channel is converted into a tube 37 when it projects beyond a small end wall 38 of the bin 32. The free end of the tube receives a continuation of the conveyor 36 and has a spout 39 at the discharge end. A manually operated crank 40 rotates the conveyor for withdrawing grain or sand from the bin 32. A bracket 41 projecting from the side wall 20 has a bearing for the inner end of the shaft 30. A bracket 42 secured to the bottom of the channel 37 has a bearing for the lower end of a shaft 43 that revolves the conveyor 36.

A belt 45 in the form of a rubber band, is trained on the pulley 31 and a pulley 46 secured to the traction wheel 17a. A second pulley 47 is secured to the shaft 30 and a belt 48 in the form of a rubber band is trained on said pulley and a pulley 49 secured to one end of a shaft 50 mounted in bearings in the spaced side walls 20 and 21 of the housing 13. Guides 51 and 52 are pivoted on the shaft 50. A pulley 53 is secured to the other end of the shaft 50 and a belt 54 is trained on said pulley and on a pulley 55 rigid with a shaft 56 carried by brackets 57 rising from the guides 51 and 52.

A beater generally designated by the numeral 60 has spaced hubs 61 from which radiate arms 62. A blade 63 is attached to the ends of a pair of the arms by leather straps 64 so that the blades will be freely movable on the ends of the arms. The hubs are secured to the shaft 56 so that the blades will be revolved by the shaft.

A cylindrical wooden roller 67 is secured axially on the shaft 50 and is revolved thereby. A second wooden idler roller 68 is secured axially to a shaft 69 which has its ends mounted in bearings formed in the outer ends of the guides 51 and 52. A canvas belt 70 is trained on the rollers 67 and 68 and is driven by the roller 67 beneath the beater 60.

The inner ends of the guides 51 and 52 provide bearings for the shaft 50 while said shaft forms a pivot for the inner ends of said guides. The guides are of an inverted V-shape in cross section with the inner ends being split. The outer ends are pointed to simulate the shape of actual guides which move through the stalks of grain for forcing the stalks which are being beaten inwardly towards the beater while directing stalks at one side of the path of travel of the combine away from the moving beater.

The guides 51, 52, the beater 60 and the idler roller 68 may be raised manually as a unit by a lever 71 having a handle 72 at the free end thereof. The inner or lower end of the lever is secured to a horizontal shaft 73 mounted in a bearing 74 secured to the beam 10. A crank arm 75 extends inwardly from the shaft 73 and has a sliding connection with a slot 76 in a bar 76a which is secured to the under face of the guide 52. A vertically disposed ratchet bar 77 has teeth 78 adapted to be engaged by the lever 71 for retaining the lever in a predetermined position when rocked for raising or lowering the outer free ends of the guides. The lower end of the bar 77 is secured firmly to the beam 10.

The beam 10 is located at one side of the housing 13 and the guide 52. The inner free end of the beam is provided with a swiveled connector 80 for attachment to a tractor. The connector permits the combine to be tilted to either side of the line of travel of the tractor.

The operation of my device is as follows:

When the toy is drawn along a surface, the traction wheels are revolved causing the pulleys 47, 49, 53 and 55 to be rotated. The hopper 27 is filled with sand, grain or other materials and the screw 29 being rotated by the shaft 30, will convey the materials to the bin 32. The screw 36 is operated manually for delivering the materials through the tube to the spout 39 whence said materials are collected in a container.

The beater 60 is revolved by the pulleys 53 and 55 in connection with the entrained belt 54. The blades will brush over the moving canvas belt 52 operated by the drum or roller 67 in simulation of a beater and header of a full scale combine. The header may be raised at will by the proper manipulation of the lever 71. The wheels 17 and 17a may be loose on the axle 11 so that the wheel 17a will drive the pulley 46 and likewise the various pulleys through the intermediary of the associated belts.

The hopper 27 is in effect the main element of the body 13 because the opposite parallel walls 20 and 21 are extended in opposite directions lengthwise of the toy to form not only a support for the hopper but bearings for the shaft 50. It will be noted from Figure 1 that the top 22 is cut away at the inner end as is the bottom panel 23 to provide an open space to receive the inner ends of the guides 51, 52 and the inner end of the belt 70 and the roller 67.

What I claim:

What I claim:

1. A toy combine comprising a frame, an axle disposed transversely of said frame contiguous to one end thereof, a ground engaging wheel

carried contiguous to each end of said axle, a body disposed adjacent said one end of said frame and supported thereon, a hopper arranged within said body and supported therein, a bin arranged exteriorly of said body in end to end relation with respect to one end of said hopper and fixedly secured to said body, a horizontally disposed rotatable spiral conveyor arranged within said hopper and extending transversely of the latter, said conveyor having one end projecting beyond said one end of said hopper and terminating in said bin, means for actuating said conveyor in response to the rotary movement of said axle for feeding the contents of said hopper into said bin, a downwardly inclined conveyor including spaced rollers and a belt trained about said rollers arranged adjacent the other end of said frame, said conveyor having the upper roller thereof positioned adjacent said hopper and pivotally mounted on said body and having the lower roller thereof supported on said frame, and means for actuating said conveyor in response to the rotary movement of said axle to thereby simulate the action of a combine.

25 2. A toy combine comprising a frame, an axle disposed transversely of said frame contiguous to one end thereof, a ground engaging wheel carried contiguous to each end of said axle, a body disposed adjacent said one end of said frame and supported thereon, a hopper arranged within said body and supported therein, a bin arranged exteriorly of said body in end to end relation with respect to one end of said hopper and fixedly secured to said body, a horizontally disposed rotatable spiral conveyor arranged within said hopper and extending transversely of the latter, said conveyor having one end projecting beyond said one end of said hopper and terminating in said bin, means for actuating 35 said conveyor in response to the rotary movement of said axle for feeding the contents of said hopper into said bin, a downwardly inclined conveyor including spaced rollers and a belt trained about said rollers arranged adjacent the other end of said frame, said conveyor having the upper roller thereof positioned adjacent said hopper and pivotally mounted on said body and having the lower roller thereof supported on said frame, and means for actuating said conveyor in response to the rotary movement of 45 said axle to thereby simulate the action of a combine, hand actuatable means extending into said bin and having an end projecting exteriorly of the latter for withdrawing the contents of said bin, and means operatively connected to said frame and said conveyor for raising and lowering the lower end of the latter.

KENNETH E. WISSLEAD.
